UNITED STATES PATENT OFFICE.

JAMES PETER KIMBLE, OF ROSE HILL, IOWA.

TRACK-CLAMP.

SPECIFICATION forming part of Letters Patent No. 477,943, dated June 28, 1892.

Application filed March 3, 1892. Serial No. 423,633. (No model.)

To all whom it may concern:

Be it known that I, JAMES PETER KIMBLE, a citizen of the United States of America, residing at Rose Hill, in the county of Mahaska and State of Iowa, have invented certain new and useful Improvements in Track-Clamps; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in clamps for railway-rails.

The object of the invention is to provide means for connecting the rails to each other to prevent them spreading; and it consists in 20 the construction and combination of the parts, as will be hereinafter fully set forth, and particularly pointed out in the claims.

In the accompanying drawings, forming part of this specification, Figure 1 is a sectional view showing the device applied. Fig. 2 is a perspective view, partly in section, showing the parts which make up the clamp detached. Fig. 3 is a perspective view showing the invention applied to a rail-joint having a 30 fish-plate.

A designates a rod, the ends of which are threaded either in the same or reverse direction, as may be preferred, and these screw-threaded portions *a a* may be of a greater diameter than the rest of the rod or of the same or less diameter, a larger diameter being preferred for the reason that the parts of the clamp which lie between the rails can be slid upon the center portion of the rod when desired.

B and B' designate adjustable clamp-nuts, which have central apertures *b* and *b'*, a portion of each of which is enlarged, as shown, the reduced portion of each aperture being 45 screw-threaded to receive the threaded ends of the rod A. Each clamp-nut has an annular shoulder *c*, which is adapted to engage with one of the clamping-heads which embrace the base-flange of the rail. The extended portion of the clamp-nut B is externally screw-threaded, as shown at *d*, for en-

gagement with the threads *d'*, formed in the enlarged portion of the aperture in the clamp-nut B'.

D and D' designate the clamping-heads, 55 which have jaws *e* and *e'*, which are adapted to engage with the base-flange of the rail. The clamp D has an aperture *f*, which is adapted to fit over the unthreaded portion of the clamp-nut B adjacent to the shoulder *c*, 60 and beyond this aperture *f* is a recess or aperture *g* of larger diameter, into which may pass the inner end of the clamp-nut B'. The clamp D' is provided with a straight-away aperture *f'*, into which passes the inner end of 65 the clamp-nut B', and, if desired, the under side of the clamp may be cut away, so that it can be readily placed over the rod A, as it may be necessary to remove said clamp and replace it with one having a jaw of a different 70 size for engagement with a fish-plate, as shown in Fig. 3.

The device hereinbefore described is adapted to be applied to the rails between the ties, and it will be observed that the fixtures at 75 end of the rod A are independently adjustable, so that the rails may be adjusted to the proper gage.

Having thus described my invention, what I claim as new, and desire to secure by Letters 80 Patent, is—

1. The combination, in a clamp for railway-rails, of a rod having threaded ends, clamp-nuts threaded for engagement therewith and with each other, and clamping-heads apertured for the passage of the clamp-nuts, said 85 heads having jaws, substantially as shown, and for the purpose set forth.

2. The combination, in a clamp for railway-rails, of a rod A, an adjustable clamp-nut 90 adapted to engage with the threaded portion of the rod, and a head having jaws, and a portion which encircles the clamp-nut, said encircling portion being cut away to provide for placing the same upon the rod, substantially 95 as shown, and for the purpose set forth.

3. The combination, with a rod A, having threaded ends, of clamp-nuts B and B', threaded for engagement with each other and provided with shoulders *c c*, and clamps D and D', 100 apertured for the passage of the clamp-nuts, the shoulders *c c* of the clamp-nuts bearing

against the outer edges of the clamps, substantially as shown, and for the purpose set forth.

4. In a rail-clamp, the combination of a rod
5 having a threaded end, an adjustable clamp-
nut threaded for engagement therewith and
provided with a shoulder *c* and an inwardly-
extending portion, a clamp carrying jaws and
provided with an aperture through which the
10 inwardly-projecting portion of the clamp-nut

passes, the shoulder *c* thereof bearing against
the exterior portion of the clamp adjacent to
said aperture, substantially as shown.

In testimony whereof I affix my signature in
presence of two witnesses.

JAMES PETER KIMBLE.
